COMBINED CAB AND BODY STRUCTURE FOR AN EARTH MOVING AND HANDLING MACHINE

Bernard Jean Marie Pierre, Crepy-en-Valois, France,
assignor to Poclain, Le Plessis-Belleville, Oise, France

Filed Oct. 22, 1974, Ser. No. 516,994

Claims priority, application France Apr. 23, 1974

Term of patent 14 years

Int. Cl. D15—04

U.S. Cl. D40—5

FIG. 1

FIG. 2

FIG. 3

FIG. 4

FIG.5

FIG.6

FIG.7

FIG. 1 is a left side elevational view of a combined cab and body structure for an earth moving and handling machine showing my new design;

FIG. 2 is a perspective view thereof;

FIG. 3 is a front elevational view thereof;

FIG. 4 is a rear elevational view thereof;

FIG. 5 is a right side elevational view thereof;

FIG. 6 is a top plan view thereof; and

FIG. 7 is a bottom plan view thereof.

I claim:

The ornamental design for a combined cab and body structure for an earth moving and handling machine, substantially as shown.
